CLAIM

The ornamental design for a shear blade component for a shear blind assembly, as shown and described.

DESCRIPTION

FIG. 1 shows a bottom perspective views of a shear blade component for a shear blind assembly.

FIG. 2 shows a top perspective views of a shear blade component for a shear blind assembly.

FIG. 3 shows a second bottom perspective views of a shear blade component for a shear blind assembly.

FIG. 4 shows a third bottom perspective views of a shear blade component for a shear blind assembly.

FIG. 5 shows a second top perspective views of a shear blade component for a shear blind assembly.

FIG. 6 shows a top perspective view of a shear blade component for a shear blind assembly in an open configuration.

FIG. 7 shows a bottom perspective view of a shear blade component for a shear blind assembly in an open configuration; and,

FIG. 8 shows a top perspective view of a shear blade component for a shear blind assembly in a closed configuration.

The broken lines rendered in FIGS. 6-8 illustrates the environment of the claimed design and forms no part thereof.
